CLAIM

I claim the ornamental design for a beverage can opener, as shown and described.

DESCRIPTION

FIG. 1 is an upper perspective view of a beverage can opener showing my new design;

FIG. 2 is a bottom view thereof;

FIG. 3 is a top view thereof;

FIG. 4 is a front view thereof;

FIG. 5 is a first side view thereof;

FIG. 6 is a second side view thereof; and,

FIG. 7 is a rear view thereof.

Only the outside edge of the beverage can opener shown in a solid line is claimed; none of the surface of the beverage can opener is claimed.
